(57) **CLAIM**

The ornamental design for a document organizer as shown and described.

DESCRIPTION

FIG. 1 is a perspective view of a document organizer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the document organizer and drawers.

The broken line portions of the document organizer in FIGS. 1-8 represent unclaimed portions of the document organizer and form no part of the claimed design. The dot-dash broken lines in FIGS. 1-8 depict the unclaimed boundary of the document organizer. The broken lines of the drawers in FIG. 8 illustrate unclaimed environment and form no part of the claimed design.

1 Claim, 8 Drawing Sheets
